UNITED STATES PATENT OFFICE.

ROY B. RICHMOND, OF CHICAGO, ILLINOIS.

MUSICAL INSTRUMENT.

Application filed October 21, 1921. Serial No. 509,304.

This invention relates to musical instruments.

It will be explained as applied to a player piano.

5 Ordinarily the notes which comprise a musical composition are produced by player pianos through the instrumentality of a perforated strip, hereinafter termed the master record. This master record usually 10 assumes the form of a roll and the production of notes is governed by the openings therein.

Such pianos are often operated by persons unskilled in music and, unless some arrangement is made for automatically varying the volume of tone, the compositions will be played without emphasis. Consequently the compositions will be expressionless and monotonous.

20 In order to overcome this objection manufacturers of the better grades of player pianos have provided for the production of expression through the instrumentality of additional perforations in the master record.

25 These additional perforations control the volume of the notes.

However, since the volume controlling perforations of a particular master record always bear a prearranged and fixed relation to the note controlling perforations thereof, the musical composition is invariably given the same emphasis. Thus there is no opportunity for variation and monotony results. Furthermore, the production of the additional perforations in each and every master record increases the expense, and emphasized or expressioned music rolls are usually sold at a considerably higher price than plain rolls.

40 One of the objects of this invention is to overcome the monotony or sameness of player piano productions.

Another object is to automatically give expression which bears no prearranged or 45 fixed relation to the master record.

Another object is to provide an attachment for a player piano which will automatically emphasize any musical composition played thereon.

50 Another object is to automatically emphasize the compositions produced from plain rolls.

Another object is to provide expression in player piano productions without incurring 55 the expense of specially prepared and relatively expensive rolls.

Other objects and advantages will herein-after appear.

In accordance with this invention the tone of the instrument is automatically modified 60 according to arbitrary, regularly or irregularly recurring variations, which are independent of and bear no fixed or prearranged relation to the master record controlling the reproduction of the musical composition. 65 Supplementing the control of the master record is an auxiliary record; for example an endless perforated tape, which independently and arbitrarily increases and decreases the volume or intensity of the tone. Thus, 70 regardless of the master record and the will of the operator, the production is given expression which destroys the objectionable monotony so often experienced in the use of automatic players. 75

An embodiment of the invention is illustrated in the accompanying drawings.

The views in the drawings are as follows:—

Fig. 1 is a diagrammatic front elevation 80 of a player piano equipped for automatic tone modification.

Fig. 2 is a diagrammatic transverse section thereof.

Fig. 3 is an enlarged side elevation of the 85 tone modifying or auxiliary controller.

Fig. 4 is an end elevation thereof.

Fig. 5 is a section on the line 5—5 of Fig. 4.

Fig. 6 is an enlarged elevation of the 90 tone modifying valve mechanism.

Fig. 7 is a plan thereof, partly in section.

Fig. 8 is a section on the line 8—8 of Fig. 6.

Fig. 9 is a plan of a portion of a perforated tape forming the auxiliary record and a diagrammatic representation of the tone modification produced by a section thereof.

In general, the player piano has a keyboard, strings and sound-board of the usual 100 type. The strings are struck by hammers 5 which correspond to the various keys. The hammers are actuated automatically by individual air controlled motors 6, commonly called "hammer pneumatics." The operations of these pneumatics are controlled in accordance with the openings in a master record usually in the form of a perforated tape or strip of paper 7. The player's feet operate treadles 8 which, by means of air exhaust bellows 9 and equalizer bellows 10, maintain a vacuum in two interconnected 105 110

vacuum chambers or "wind chests" 13 and 14. Each of the hammer pneumatics 6 is connected separately with wind chest 14. Perforated tape 7 passes over a tracker bar 15 provided with openings. These openings in the tracker bar are adapted to be covered by tape 7 except when the holes therein register with the corresponding tracker bar openings. When the openings register, the individual hammer pneumatics are caused to operate the hammers to strike the corresponding strings.

In addition to the customary pneumatic player action for controlling the reproduction of the notes in accordance with the openings in the master-record an automatic tone modifier is provided.

The tone modifier comprises, in general, an auxiliary controller 16. Controller 16 governs the operation of a pair of tone controlling valves 17 and 18 in accordance with the openings in an auxiliary record, which may take the form of an endless perforated paper tape or strip 19. Valve 17 controls a pair of air controlled motors 20, called "hammer rail" pneumatics. Valve 18 regulates the passage of air through a pipe 21 which connects wind chest 13 with wind chest 14.

Hammer rail pneumatics 20 control the striking distance of hammers 5 by respectively moving corresponding sections of a two sectioned or "divided" hammer rail 22 towards the strings. Suitable arrangements whereby pneumatics 20 may move the hammer rail sections are well known in the art. Valve 18 regulates the flow of air through pipe 21 and thereby controls the striking force of the hammer pneumatics which actuate the individual hammers.

The tone controlling openings in tape 19 are prearranged as to number and position in any desired manner, so that, as the master and auxiliary records simultaneously control the action of the hammers, the tone of the notes produced is arbitrarily varied regardless of the will of the operator and the particular master-record being used.

The endless perforated tape or auxiliary record 19 is actuated by an air motor 23. Motor 23 may be the motor which ordinarily actuates the master-record and forms part of the usual automatic player piano action. The auxiliary tape feeding mechanism is operatively connected to motor 23 by means of a clutch 24 and an intermediate speed reducing transmission system. Clutch 24 is connected to and disconnected from air motor 23 by a control lever 25.

The transmission system of the auxiliary controller comprises a unit having a pair of side plates 29, and is preferably secured to an end wall of the piano by any suitable means, such as clips 30. The transmission system has a rotatable shaft 31, on which

clutch 24 is mounted. A sprocket wheel 32 mounted on shaft 31 actuates a sprocket chain 33. Chain 33 passes over a sprocket wheel 34. Wheel 34 actuates a pinion 35. Pinion 35 turns a gear wheel 36. A spool 37 is operatively connected to and rotated by wheel 36. An auxiliary tracker bar 38 is positioned between spool 37 and an idler 39. Tape 19 is looped about spool 37 and idler 39 so as to pass over the face of auxiliary tracker bar 38. The driving force of motor 23 is thus transmitted through the speed reducing system to rotate spool 37 and move tape 19 at a relatively slow speed over the auxiliary tracker bar.

Tracker bar 38 has a pair of openings 40 therein. Openings 40 are respectively connected by one of a pair of tubes 41 to a pair of tone controlling pneumatics 42 and 43. Pneumatics 42 and 43 are connected to wind chest 13 by a pair of tubes 44.

Auxiliary record 19 is provided with a plurality of perforations 45, longitudinally aligned in two parallel groups, one near each edge of the tape. The arrangement is such that the perforations of each group may register with a corresponding tracker bar opening 40 during one complete revolution of tape 19. Tracker bar openings 40 are covered by the tape except when tape perforations 45 register therewith. When the perforations in tape 19 register with their corresponding opening in tracker bar 38, the vacuum which normally holds tone controlling pneumatics 42 and 43 open is reduced, and the corresponding pneumatic collapses.

Tone controlling pneumatics 42 and 43 are each provided with an angle arm 46. Each angle arm 46 has a pawl 47 pivoted thereto. Pawls 47 are adapted to move a plunger 48 in opposite directions. Normally, or when pneumatics 42 and 43 are uncollapsed, pawls 47 rest upon corresponding tripper bars 49. Plunger 48 is provided with two similar groups of teeth 50, one group being on each side of its center. Upon the collapse of either of the pneumatics 42 or 43, the corresponding pawl 47, which is operated thereby, is pushed outwardly. This outward movement continues until pawl 47 clears its tripper bar 49, whereupon the pawl drops down and engages the nearest tooth 50 on plunger 48. The movement of the pawl continues, pushing the plunger with it, until the corresponding tone controlling pneumatic has completely collapsed. Each collapse of pneumatic 42 moves the plunger to the left a distance corresponding to one tooth, and each collapse of pneumatic 43 moves the plunger substantially the same distance in the reverse direction or to the right.

Tone controlling pneumatics 42 and 43 are biased toward their normal or uncollapsed

condition by corresponding springs 51. These springs retain the pneumatics extended as long as openings 40 in auxiliary tracker bar 38 are out of register with perforations in the auxiliary tape. Substantially U shaped loops 52 provide guideways for plunger 48 and serve to keep the same in longitudinal alignment with valves 17 and 18.

10 Valves 17 and 18 are mounted on a rod 53 which is connected to plunger 48 by a union 54. Consequently the collapse of tone controlling pneumatics 42 or 43 moves valves 17 and 18 in opposite directions. Union 54 is secured at one end to a screw eye 55 mounted on plunger 48 and at the other end is adjustably secured to rod 53 between two adjusting nuts 56. Valves 17 and 18 are clamped between adjusting nuts 57 which are threaded onto rod 53. The adjustment and position of the valves may be varied by turning nuts 56 and 57.

20 An air-tight gate box 58 is inserted in air pipe 21. Valve 18 is mounted in the gate box so as to open and close an air port 59 therein as the valve is actuated in opposite directions by the movement of plunger 48. Port 59 connects pipe 21 with the bottom of gate box 58 so that valve 18 regulates the flow of air through pipe 21 from wind chest 13 to wind chest 14. The more port 59 is opened, the greater the vacuum in wind chest 14 and the more intense the stroke produced by hammer pneumatics 6. Since, 30 in the illustrated embodiment, there are four teeth 50 which are engageable by each pawl 47, port 59 may be opened or closed in four steps or stages. Consequently the tone modification produced by port 59 has, as a maximum, four steps in each direction. That is, 40 the tone can be softened in four steps and strengthened in four steps.

45 Ports 60 and 61 are provided in an extension 62 of gate box 58. These ports are opened and closed by valve 17 in its movement back and forth. Ports 60 and 61 are connected to tubes 65 and 66 by means of tubes 67 and 68, respectively. Tubes 65 and 66 connect a pair of expression buttons 69 and 70 with hammer rail pneumatics 20 so that the operator may, if he desires, manually control the positions of the hammer rail sections. Pneumatics 20 in collapsing each actuates a rod 71. Rods 71 connect pneumatics 20 with the respective sections of the 55 divided hammer rail 22 in such a way that the collapse of a pneumatic moves the corresponding hammer rail section toward the strings, while the expansion of either pneumatic moves the corresponding section away from the strings.

60 Ports 60 and 61 are each connected through tubes 66 and 68 and tubes 65 and 67, respectively, to the pneumatics 20. 65 When port 60 is opened by valve 17 the

pneumatic 20 connected thereto is collapsed by the flow of air through tubes 68 and 66 thereby throwing the corresponding section of the hammer rail forward. This movement of a hammer rail section shortens the 70 striking distance of the hammers associated therewith. The collapse of the other pneumatic 20 occurs when port 61 is opened so as to permit the escape of air through tubes 67 and 65. Since the striking distance of the 75 hammers depends upon the positions of the divided hammer rail and the positions of the hammer rail sections are controlled by the collapse of pneumatics 20, movement of valve 17 controls the striking distance of the 80 hammers.

85 Valves 17 and 18 and the ports controlled thereby are so related that when port 59 is substantially closed ports 60 and 61 are both open. When port 59 is partly opened, because of the movement of plunger 48 one step to the right, port 60 is closed. On the next step of the plunger port 59 is further opened, port 60 remaining closed, but port 61 is not closed. On the next step port 59 90 is opened still more and port 61 is closed. On the final step port 59 is completely 95 opened. The reverse movement of plunger 48 produces the opposite effects. On each step port 59 is restricted and on the second and fourth steps, respectively, ports 61 and 60 are opened.

100 In Figs. 6 and 7 valves 17 and 18 are shown in their extreme left hand positions with port 59 substantially closed and ports 60 and 61 open. In this position of the valves the intensity of the hammer strokes is weakened on account of the slight vacuum in wind chest 14. The striking distance of the hammers is shortened on account of 105 pneumatics 20 being collapsed. The corresponding tone or degree of expression produced when the valves are in the position shown is the lowest or what is known in the art as "pianissimo", ordinarily designated 110 by the symbol "PP".

115 When valves 17 and 18 are in their extreme right hand positions port 59 is completely open and ports 60 and 61 are closed. In this position of the valves the intensity 120 of the stroke and the striking distance of the hammers are at a maximum since port 59 is unobstructed and both pneumatics 20 are uncollapsed. The corresponding tone or degree of expression produced is the loudest or what is known in the art as "fortissimo" 125 ordinarily designated by the symbol "FF".

130 The three tones or degrees of expression intermediate the "pianissimo" and the "fortissimo" which are designated in the art by the symbols "P", "MF", and "F" are produced in the previously described intermediate positions of valves 17 and 18. Thus the degree of expression "P" occurs when 135

plunger 48 is in the position wherein port 60 is closed and the degree "F" occurs when both ports 60 and 61 are closed.

These degrees of expression, which are automatically produced in accordance with the holes in the auxiliary record, can be slightly modified by the operator actuating the pedals faster or slower so as to change the vacuum in wind chests 13 and 14. The experienced operator is thereby enabled to produce an infinite number of degrees of expression differing from, or in effect superimposed upon, the predetermined degrees of expression produced by the auxiliary record.

Valves 17 and 18 move step-by-step, either to the right or the left, so that the tones are increased or decreased by only one step at a time.

Since plunger 46 is actuated by the collapse of pneumatics 42 and 43, which in turn are collapsed by tracker bar openings 40 coming into register with perforations in the auxiliary record, the movement of the auxiliary record over its tracker bar controls the position of valves 17 and 18 and the resulting degrees of expression. Simultaneous collapse of pneumatics 42 and 43 is prevented by spacing perforations 45 so that only one opening 40 is in register with a perforation at any one time.

Perforations 45 along one edge of the tape collapse pneumatic 42 and thereby cause plunger 48 to actuate valves 17 and 18 to the left. The perforations along the opposite edge of the tape cause the collapse of pneumatic 43 and thereby cause the plunger and valves to move to the right.

A fragment of a typical expression curve 72 is shown in Fig. 9 in connection with the arrangement of perforations in the auxiliary record which will produce the changes of expression. Tape 19 is represented as moving to the left. Registry of any perforation 45 in the bottom row with an opening 40 in tracker bar 38 causes pneumatic 42 to collapse. The collapse of pneumatic 42 moves valves 17 and 18 one step to the left thereby instantaneously lowering the volume of tone or expression. Similarly registry of a perforation 45 in the top row causes pneumatic 43 to collapse. The collapse of pneumatic 43 moves the valves to the right and raises the volume of tone. In the diagram the tone is indicated as starting at "P" where it remains until the first bottom perforation registers with its opening when the tone drops to "PP" where it remains until a top perforation registers with its opening when the tone returns to "P". Three successive perforations along the top raise the tone through "MF" and "F" to "FF". Four successive bottom perforations lower the tone to "PP" through the intermediate steps and three successive perforations in the top row again raise the tone to

"F". The longitudinal spacing between any two perforations determines the period of any one degree of expression and can be varied as desired.

Since the modifications of tone depend on the striking distance of the hammers and the striking force of the hammer pneumatics, the auxiliary controller, by the operation of valves 17 and 18, independently regulates the tone of the notes produced through regular player action and the master record.

It is unnecessary to synchronize the movements of the master and auxiliary records. The master record may be started without regard to its relation to the openings in the auxiliary record; it is only necessary to insert or rewind the master record and start playing. Thus, since the tone controlling openings in the auxiliary record need not and usually will not bear the same relation to the note controlling openings in the master record upon repetitions of the same production, a great variation in expression is possible. Monotonous playing is consequently practically impossible.

Having described my invention what I claim as new and desire to secure by Letters Patent, is:—

1. The combination with an automatic piano having strings, hammers for vibrating the strings and a master record for controlling the action of the hammers to produce a musical composition, of an auxiliary record operated automatically and independently of the master record to vary the length of the hammer strokes and thereby give expression to the composition.

2. An automatic stringed instrument having hammers for vibrating the strings and master-record mechanism for causing the hammers to vibrate the strings, of an auxiliary record for varying the length of the hammer strokes to regulate the volume, and an auxiliary controller automatically operating said auxiliary record entirely independently of the master record mechanism and controlling said auxiliary record.

3. In an automatic piano in which a master record mechanism controls the production of the notes, an automatic auxiliary controller driven independently of any fixed relation to the master record, and volume modifying auxiliary record controlled by the auxiliary controller and acting independently of the master record mechanism.

4. In a musical instrument in which a master record automatically controls the production of notes, means for controlling the volume of the notes, independently of note production, an auxiliary record for controlling said means, and automatic mechanism for driving the auxiliary record independently of any fixed relation to the master record.

5. The combination with a player piano,

having strings for producing the notes, hammers for striking the notes, and hammer operating mechanism controllable by a master record, of an automatic tone controller comprising an auxiliary record, means for driving the auxiliary record independently of any fixed relation to the master record, and means for varying the length of the hammer strokes in accordance with the auxiliary record.

6. In a musical instrument the combination of note producing elements, means for causing said elements to produce their corresponding notes, mechanism controllable by a master record for causing said means to influence said elements, tone modifying means acting independently of the note producing means for varying the volume of sound produced by said elements, an auxiliary record for controlling said tone modifying means, and driving means for actuating the auxiliary record independently of any fixed relation to the master record.

7. The combination with a player piano having strings, hammers for striking the strings and master control mechanism for controlling the operation of the hammers, said mechanism including a series of pneumatic devices controlled by perforations in a master-record tape and means for carrying and moving the tape, of an independent auxiliary tone controller for varying the effect of the hammers upon the strings, said

auxiliary controller including pneumatic devices controlled by an auxiliary record driven independently of any fixed relation to the master-record tape, and separate and independent means for moving the auxiliary record.

8. In a piano a master controller for governing the production of notes in accordance with perforations in a master record, an auxiliary record, independent means controlled by the auxiliary record for varying the volume of the notes produced through the action of the master record, and driving mechanism for the auxiliary record, said mechanism moving the auxiliary record independently of any fixed or predetermined relation to the master record.

9. A musical instrument comprising note producing mechanism, a master controller controlled by a master record for governing the note producing mechanism, volume governing mechanism for independently controlling the volume of tone produced by the note producing mechanism, and an auxiliary record physically independent of the master record and arbitrarily and automatically influencing the volume governing mechanism independently of any fixed relation to the master record.

In testimony whereof I hereunto subscribe my name.

ROY B. RICHMOND.
